SEWING MACHINE

William A. Wheaton, Lynn, Mass., assignor to
 United Shoe Machinery Corporation, Borough
 of Flemington, N. J., a corporation of New
 Jersey

Application November 13, 1939, Serial No. 303,970

4 Claims. (Cl. 112—46)

The present invention relates to sewing machines, and more particularly to a simplified and improved machine for securing the welt to the margin of an unlusted upper in the manufacture of what are commonly known as pre-welt shoes.

In sewing the welt to the margin of an unlusted shoe upper, it is desirable to gather or pucker the upper, especially at the toe end of the shoe, to facilitate fitting the upper over a last during the subsequent manufacture of the shoe. To effect a substantial puckering of the upper, it has, heretofore been considered necessary to provide the sewing machine with a separate or additional upper feeding mechanism to act on the upper during the formation of the stitches of the seam, and form a slight fold or pucker in the upper between successive passages of the sewing needle through the work. The addition of this upper feeding mechanism, however, renders the machine more complicated both in construction and operation and also by occupying a formerly open space in proximity to the sewing point obstructs the view of the operator and increases the difficulty of properly manipulating the work to secure satisfactory results.

The object of the present invention is to provide a sewing machine which does not embody a separate upper feeding mechanism, but which nevertheless is capable of puckering the upper in a satisfactory manner during the sewing of a welt to the margin of the unlusted upper. With this object in view, the invention contemplates the provision, in a sewing machine adapted to sew the welt to the margin of an unlusted shoe upper, and comprising a work feeding instrument which pierces the work, of a tension device constructed and arranged to act on the welt so as to cause a backward displacement of the welt on the upper after each feeding movement, such displacement, in connection with the effect produced by the possible contraction of the tensioned welt between successive stitch holes, and the effect possibly produced by the operator in bending the upper over the work support and forcing the margin into the line of feed, being sufficient to effect a substantial puckering of the upper during the formation of the stitches of the seam.

Sewing machines adapted to sew a welt to the margin of an unlusted shoe upper usually comprise a work piercing feeding instrument in the form of either an awl or a needle, and a work clamping presser-foot which is lifted during each stitch forming cycle while the work is being fed. In developing the present invention a machine

of this character has been provided with a tension device, arranged to act upon the welt, and of a character to cause the feeding instrument during its feeding movement in the line of feed to tension that portion of the welt extending between the feeding instrument and the tension device. This portion of the welt remains under tension until the feeding instrument withdraws from the welt at which time, although the welt and upper are still clamped between the presser-foot and work support, a slight backward movement is imparted to the welt by reason of the heavy tension to which it has been subjected. This backward movement of the welt tends to displace the welt on the upper, thereby making the distance between the stitch holes shorter on the welt than on the upper so that when the thread connecting adjacent stitch holes is tightened in completing a stitch, there is a tendency to gather or pucker the upper on the welt. Inasmuch as the upper to which the welt is being attached is not under tension, this backward movement of the welt also tends to slide the welt over the upper, the backward movement of which is resisted by contact with the work support, and to form a slight fold in the upper close to the last stitch hole. As a final result of this displacement of the welt with relation to the upper, a substantial puckering of the upper is produced, the puckering effect possibly being augmented somewhat by the contraction of the portion of the welt between the last stitch and the feeding instrument when the presser foot is lifted, which movement of the presser-foot takes place after the feeding instrument has again penetrated the work preparatory to another feeding movement in the line of feed. The puckering effect may also be augmented somewhat by the manipulation of the upper by the operator during the sewing operation, and particularly while sewing around the toe of the shoe. To enable the upper to be readily bent over the work support at the toe portion of the shoe to bring the upper and welt more nearly into the relative position which they occupy in a completed shoe, and to permit the operator to force the margin of the upper into the line of feed, the work support of the machine is preferably made narrower than in machines in common use, and the work engaging surfaces on each side of the sewing point are rounded off.

In embodying the present invention in a sewing machine adapted to sew the welt to the unlusted upper of a shoe, it is preferred to arrange the work supporting and guiding devices in such a

manner as to cause the work piercing feeding instrument to enter the work from the side on which the upper is located. By arranging the parts of the machine in this manner, the work feeding instrument, during its retracting stroke, withdraws first from the welt and thus may act in some degree to hold the upper against backward movement with the welt and cause the hole in the welt to be displaced with relation to the hole in the upper. Also in embodying the present invention in a sewing machine adapted to sew the welt to the margin of an unlasted shoe upper, it is preferred to utilize a sewing machine which forms a chainstitch seam, and to arrange the work supporting and guiding devices in a manner to cause the chain of the seam to be laid on the upper, since it has been found that the chain side of a chainstitch seam has a tendency to gather or pucker to a slight extent the material on that side of the seam.

The several features of the present invention will be clearly understood from the following description taken in connection with the accompanying drawing in which a form of the invention is illustrated as embodied in a sewing machine of well-known construction, so much only of the machine being shown as is necessary to indicate the connection of the present invention therewith.

In the drawing, Figure 1 is a view in front elevation of a portion of a sewing machine embodying the present invention; Figure 2 is a detail sectional view of the work done on the machine; Figure 3 is a detail plan view of the welt guiding and tensioning device, together with its supporting bracket with which the machine is provided; Figure 4 is a view in side elevation of the parts shown in Figure 3, looking towards the right; Figure 5 is a view in side elevation of the same parts looking towards the left; and Figure 6 is a detail view illustrating somewhat diagrammatically the appearance of the welt and upper at the time the seam is being sewed around the toe of the shoe.

The sewing machine, parts of which are illustrated in Figure 1, is provided with a work support 2, a presser-foot 4, a straight awl 6, a straight hook needle 8, a cast-off 10, and a looper 12. These parts, except for changes in the work support and presser-foot hereinafter referred to, being constructed and arranged to operate as in the well-known Puritan sewing machine. For a full disclosure of the construction and mode of operation of a machine of this type, reference may be had to the pending application of Ashworth S. N. 303,522 filed November 9, 1939.

The welt guiding and tension device with which the machine has been provided comprises two flat plates 14 and 16 between which the welt passes on its way to the sewing point. The plate 14 is stationary and is formed integrally with a supporting bracket 18. The plate 14 projects horizontally from the upper end of the bracket, the lower end of which extends at an angle to the body portion of the bracket and is secured to the bed plate 20 of the sewing machine by bolts passing through slots 22 in the lower end of the bracket. The plate 16 of the welt tension device is mounted upon the plate 14 and is yieldingly forced towards the plate 14 to exert the desired frictional resistance to the travel of the welt between the plates. To support the plate 16 on the plate 14, the plate 16 is provided with a hole at its rear end through which loosely

passes a pin 24 projecting from the plate 14, and midway of its ends the plate 16 is provided with a slot 26 through which passes loosely a stud 28 which screws into the plate 14. The plate 16 is forced yieldingly towards the plate 14 by means of a spring 30 coiled around the stud 28 and interposed between a knurled head 32 at the outer end of the stud and a washer 34 loose on the stud and bearing against the plate 16. By rotating the screw threaded stud 28, the spring 30 can be adjusted to cause the desired pressure to be exerted on the welt. The welt passes from the welt tension device through a guiding opening 35 in the presser-foot and, in order that welts of different widths may be properly guided and controlled, the welt tension device is provided with relatively adjustable guiding pins 36 and 38 which engage the side edges of the welt. The pin 36 is rigid with the plate 14 and projects through a slot 40 in the plate 16 and the pin 38 is rigid with the plate 16 and projects through a slot 42 in the plate 14. To permit a relative adjustment of the pins 36 and 38 to accommodate welts of different widths, the pin 24 which supports the plate 16 at its rear end extends through a slot 44 in the plate 14 and is adjustably secured in the slot by means of a nut 46 mounted on the projecting end of the pin and cooperating with a collar 48 on the pin to clamp the pin in adjusted position. An adjustment of the pin 24 in the slot 44 of the plate 14 moves the plate 16 longitudinally to effect the desired adjustment of the pin 38 on the plate with relation to the pin 36, this longitudinal movement of the plate 16 being permitted by the slot 40 in the plate 16 and the slot 42 in the plate 14.

In utilizing the illustrated machine to sew a welt to the margin of an unlasted upper, the welt is threaded through the welt tension device and through the slot 35 in the presser-foot and the upper, indicated at 50, is located in the machine beneath the welt indicated at 52, the edges of the welt and upper being accurately aligned by an edge gage indicated at 54 in Figure 1. During the sewing operation, the upper is bent over the work support 2 to cause the welt and upper to assume as nearly as possible the relative position which they will have in the completed shoe. To facilitate this pending operation, the work support is somewhat narrower than the support ordinarily used in this type of machine, and is rounded off on its upper surface both in front of and behind the sewing point as clearly indicated in Figure 1. The machine forms a chainstitch seam, with the chain of the seam laid on the upper. The natural tendency of a chainstitch seam is to compress the materials more upon the chain side of the seam than on the opposite side and this fact, together with the manipulation of the upper in bending it over the work support tends to facilitate the puckering of the upper, especially in sewing around the toe of the shoe. The puckering effect resulting from the location of the chain of the seam and the manipulation of the upper is, however, very slight, and the principal and substantial puckering effect produced by the machine is due to the action of the welt tension device. In the operation of the machine, as fully set forth in the Ashworth pending application above referred to, the work is fed by the needle, which enters the work from below, passing upwardly, first through the upper and then through the welt, into the position indicated in Figure 1. At this time the work is

clamped between the presser-foot and the work support. After the needle passes upwardly through the work, the presser-foot is raised and the needle is moved to the left, as viewed in Figure 1, the distance of a stitch length. During this movement, the portion of the welt between the needle and the welt tension device is tensioned, the amount of tension being considerable on account of the heavy pressure exerted upon the welt by the plates of the tension device. At 10 the end of the feeding movement, the presser-foot descends to clamp the work against the work support. The needle now withdraws and as it passes downwardly through the welt and upper, the welt is first released, and while the upper is momentarily held from movement in the line of feed by the needle, the tension to which the welt has been subjected, causes the welt to move backwardly slightly, thereby tending to displace the hole in the welt with relation to the hole in the upper. As the needle completes its downward movement, the upper as well as the welt is released, and although the welt and upper are still clamped between the presser-foot and the work support, the tension to which the welt continues 15 to be subjected causes a further backward movement of the welt carrying the upper with it. The backward movement of the upper is, however, resisted by the friction exerted on the upper by the surface of the work support so that the welt moves further than the upper, and a slight fold is made in the upper between the last needle hole and the point where the needle next pierces the work. The work remains clamped between the presser-foot and the work support during the backward feeding movement of the needle and until the needle again passes upwardly through the work to the position indicated in Figure 1. At this time the portion of the welt between the preceding needle hole and the needle is still under some degree of tension and, as the presser-foot rises to permit the work to be fed, this portion of the welt is released and if it has been stretched to any extent, it is allowed to contract to its original condition, thereby still further shortening the distance between the last two needle holes and augmenting the puckering effect on the upper. The effect of the contraction of this portion of the welt is in any event, however, extremely slight, the substantial puckering effect on the upper being produced by reason of the strong pull exerted on the welt during the feeding movement of the needle against the resistance offered by the welt tension device, which resistance must be sufficient to produce an appreciable backward displacement of the welt with relation to the upper during the formation of each stitch.

The nature and scope of the present invention having been indicated, and a machine embodying the invention having been specifically described, what is claimed is:

1. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work after the work is again clamped, and means for effecting a substantial puckering of the upper

5 during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work.

2. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 10 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said work feeding instrument being arranged to enter the work from the side opposite to that on which the tension device is located.

3. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 15 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said work feeding instrument being arranged to enter the work from the side opposite to that on which the tension device is located.

4. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 20 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 25 on the upper.

5. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 30 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 35 on the upper.

6. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 40 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 45 on the upper.

7. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 50 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 55 on the upper.

8. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 60 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 65 on the upper.

9. A sewing machine for attaching the welt to the unlasted upper of a pre-welt shoe having, in combination, a work support and a presser foot to receive between them a superposed welt and upper, the presser foot being constructed, arranged and operated to clamp, release and again clamp the work during each stitch forming and work feeding cycle, work feeding and stitch forming devices comprising a work piercing feeding instrument constructed, arranged and operated to pierce the work while clamped, to feed the work while released and to withdraw from the work 70 after the work is again clamped, and means for effecting a substantial puckering of the upper during the formation of the stitches of the seam comprising a tension device acting on the welt constructed and arranged to cooperate with the work piercing feeding instrument to produce sufficient tension on the welt during each work feeding movement to cause a backward displacement of the welt on the upper as the piercing feeding instrument leaves the work, said stitch forming devices being constructed and arranged to form a chainstitch seam with the chain laid 75 on the upper.

constructed and arranged to cooperate with the work piercing feeding instrument to produce sufficient tension on the welt during each work feeding movement to cause a backward displacement of the welt on the upper as the piercing feeding instrument leaves the work, said stitch forming devices comprising a hook needle, and

devices cooperating therewith to form a chain-stitch, and means for guiding the welt and upper with the upper at the needle side of the work whereby the chain of the seam is laid on the upper.

WILLIAM A. WHEATON.
